UNITED STATES PATENT OFFICE.

WALTER OPEL, OF LEIPZIG, GERMANY.

METHOD OF MAKING EMBOSSED REPRODUCTIONS OF OIL PAINTINGS.

1,412,131.

Specification of Letters Patent. Patented Apr. 11, 1922.

Application filed October 11, 1918. Serial No. 257,818.

To all whom it may concern:

Be it known that I, WALTER OPEL, a citizen of the German Empire, residing at Leipzig, have invented certain new and useful 5 Improvements in the Method of Making Embossed Reproductions of Oil Paintings, of which the following is a specification.

Reproductions of oil paintings in form of pictures or postcards are known, which have 10 been embossed to appear as if having the grain of the oil paint, as such is applied by the artist. Such reproductions therefore have raised portions, and on the reverse side of the reproductions there will naturally be 15 corresponding indents. With postcards it would be inconvenient to have to write across such indented portions. With pictures it is immediately apparent that the picture is an embossed reproduction. These 20 drawbacks are avoided by covering the back of the pictures with a piece of paper, whereby the back assumes a plane surface. Such covering with paper is performed either by coating the back of the picture with an adhesive and pressing the piece of covering paper against it, or the covering paper is 25 coated with the adhesive and pasted to the back of the picture. In both instances the moisture of the adhesive will penetrate into 30 the indents and this moisture will cause the embossing to flatten down again. The raised embossed parts will therefore lose their initial clearness and all fineness of embossing of the picture will be lost. It is the 35 object of the present invention to prevent such flattening of embossed parts of the picture while it is being backed.

Hitherto so called postcard pasteboard was used for making such pictures, this 40 being a cellulose paper which has been calendered with the aid of caseine, size and chalk. The chalk was applied either to face and back or only to the face. The ob-

ject is to prepare the paper particularly well for the chromoprinting. Such paper was 45 heretofore used for making the postcards and pictures intended as reproductions of oil paintings. These papers are, however, of a highly hygroscopic character and will absorb the moisture of the adhesive in large 50 quantities, so that the embossing will exceedingly lose in fineness.

This disadvantage is, now, obviated by rendering the paper indifferent towards moisture before it is embossed, by applying 55 to the back of the paper to be embossed an insulating material such as paint, varnish, silicious varnish or the like. The subsequently embossed paper may then be backed in the usual manner.

In the accompanying drawing, a section through an embossed picture is represented resembling the brush grain of an oil painting. A is the embossed paper with the oil paint grain. The picture side is at a. b is 60 the insulating material. C is the coat of adhesive applied after embossing and D is the 65 backing paper. The paper A need not necessarily consist of one single layer but may also be built up of several layers which are 70 then embossed together.

What I claim as new and desire to secure by Letters Patent of the United States, is:—

The method of making embossed reproductions of oil paintings, consisting in applying to the back of the printed paper intended to be embossed a moisture-insulating 75 material, embossing such paper and backing the same in the usual manner.

In testimony whereof I affix my signature in presence of two witnesses.

WALTER OPEL.
